(57) **CLAIM**

The ornamental design for a heating device and a thermostat mount assembly, as shown and described.

DESCRIPTION

FIG. 1 is an isometric view of a heating device and a thermostat mount assembly of the present invention according to one embodiment;

FIG. 2 is a front elevational view of the heating device and thermostat mount assembly of FIG. 1;

FIG. 3 is a rear elevational view of the heating device and thermostat mount assembly of FIG. 1;

FIG. 4 is a right side elevational view of the heating device and thermostat mount assembly of FIG. 1;

FIG. 5 is a left side elevational view of the heating device and thermostat mount assembly of FIG. 1;

FIG. 6 is a top plan view of the heating device and thermostat mount assembly of FIG. 1;

FIG. 7 is a bottom plan view of the heating device and thermostat mount assembly of FIG. 1;

FIG. 8 is an isometric view of a heating device and a thermostat mount assembly of the present invention according to another embodiment;

FIG. 9 is a front elevational view of the heating device and thermostat mount assembly of FIG. 8;

FIG. 10 is a rear elevational view of the heating device and thermostat mount assembly of FIG. 8;

FIG. 11 is a right side elevational view of the heating device and thermostat mount assembly of FIG. 8;

FIG. 12 is a left side elevational view of the heating device and thermostat mount assembly of FIG. 8;

FIG. 13 is a top plan view of the heating device and thermostat mount assembly of FIG. 8; and,

FIG. 14 is a bottom plan view of the heating device and thermostat mount assembly of FIG. 8.

The broken lines are for the purpose of illustrating environmental structure and form no part of the claimed design.

1 Claim, 14 Drawing Sheets
